FOUL INDICATOR FOR ATHLETIC CONTEST OR THE LIKE

Eugene M. Sorensen, 865 Highview Terrace,
Lake Forest, Ill. 60045

Filed Feb. 23, 1967, Ser. No. 5,927

Term of patent 14 years

(Cl. D72—1)

FIG. 1 is an upper front perspective of a foul indicator for athletic contest or the like, showing my new design; and

FIG. 2 is a rear bottom perspective of such design. The cords and clamps shown in broken lines in FIGS. 1 and 2 are included for illustrative purposes only.

What is claimed is:

The ornamental design for a foul indicator for athletic contest or the like as shown and described.
